UNITED STATES PATENT OFFICE.

JOHN H. ZIMMERMANN, OF WILKINSBURG, PENNSYLVANIA, ASSIGNOR TO WESTINGHOUSE ELECTRIC & MANUFACTURING COMPANY, A CORPORATION OF PENNSYLVANIA.

TERMINAL STRUCTURE FOR ELECTRICAL APPARATUS.

No. 921,053.

Specification of Letters Patent.

Patented May 11, 1909.

Application filed November 4, 1905. Serial No. 285,860.

To all whom it may concern:

Be it known that I, JOHN H. ZIMMERMANN, a citizen of the United States, and a resident of Wilkinsburg, in the county of 5 Allegheny and State of Pennsylvania, have invented a new and useful Improvement in Terminal Structures for Electrical Apparatus, of which the following is a specification.

10 My invention relates to terminal structures for electrical apparatus and has special reference to such structures as are adapted for use with electrical measuring instruments.

The object of my invention is to provide a 15 terminal structure that shall be simple and durable and that shall adequately support a plurality of terminal pieces in an inclosing casing from which they are suitably insulated.

20 In electrical measuring instruments having metallic inclosing casings, it is desirable to provide hollow, integral projections for the support and protection of the instrument terminals. When such projections are provided, it is necessary to securely fasten the 25 terminal pieces in position and to insulate them from the inclosing casings to avoid short-circuiting the instrument leads, and openings are preferably provided through 30 the casing walls in order to facilitate attachment to and detachment from external circuits.

35 My invention provides an insulating partition between the interior of the main body of the instrument and the terminal casing, which also serves, in combination with a plurality of insulating cap bushings that are attached to the several terminal pieces and engage openings in the outer wall of the casing, to hold the terminal pieces in position.

40 In the accompanying drawings, Figure 1 is a view, partially in side elevation and partially in section, of a portion of an instrument equipped with my invention, and Figs. 45 2, 3, 4 and 5 are detail views of the terminal support shown in Fig. 1.

45 Referring to the drawings, an electrical measuring instrument casing 1 is provided with a projection 2 which constitutes a terminal casing having a detachable front wall 3 and a plurality of openings 4 in its top wall. The instrument may be provided, in the usual manner, with a detachable face cover and with a plurality of similar ter-

55 minal members 5, which are preferably assembled with a pair of insulating plates 6 and 7 before they are placed in position in the instrument. The plates 6 and 7 are constructed of hard insulating material, such as fiber, and are respectively provided with 60 two sets of similar openings 8 and 9 which are so constructed as to fit the inner extremities of the terminal members 5, and when the plates are in their operative positions, the plate 6 engages shoulders 10 on 65 the members 5 and fits into recesses 11 that are formed in the members, adjacent to the shoulders.

70 The plates 6 and 7 are provided with holes 12 to receive a plurality of binding screws 13 and the openings 8 and 9 are so located that when the plate 6 has been forced into the recesses 11 in the terminal members and the plate 7 is held in engagement with the plate 6, the holes 12 in the two plates are in alignment. In this way, the terminal members are rigidly held in position relative to each other and to the instrument by the plates 6 and 7 when said plates are fastened in position between the main body of the instrument casing and the terminal casing. The 75 opposite ends of the terminal members 5 extend into the openings 4 in the top wall of the terminal casing and are insulated therefrom by a plurality of cap bushings 14 of insulating 80 material which are screw-threaded onto the ends of the terminal members and fit into 85 said openings.

90 In order to prevent removal or gradual loosening of the cap bushings 14, each of them is provided, near its inner end, with a flange 15 which is of greater diameter than the opening 4 and fits against the inner face of the top wall. The bushings 14 are further provided with inner, annular projections 16, which so engage the ends of the terminal members that after the latter are fastened in position by the plates 6 and 7 it is impossible to remove the caps without dismembering the terminal structure.

95 The detachable wall 3 of the terminal casing allows access to a plurality of set-screws 17, by means of which conductors from external circuits may be clamped to the terminal members.

100 A plate 18 of some flexible material, such as felt, is also provided in order to prevent dust from working through the terminal cas-

ing into the instrument and is held in position by metal strips 19 which are clamped by the binding screws 13 on top of the plate.

Although I have illustrated a specific structure, I desire that variations in size, form and arrangement of details which do not depart from the spirit of my invention shall be included in its scope.

I claim as my invention:

10 1. The combination with a terminal casing for electrical instruments, of a plurality of notched terminal members in said casing, supporting and insulating means for said members comprising a pair of insulating plates which are located between the interior of the instrument and the terminal casing and one of which engages the notches in said 15 terminal members, and cap bushings attached to the terminals and fitted into openings in the outer wall of the casing.

20 2. The combination with a terminal casing for electrical instruments, of a plurality of terminal members located therein having similar lateral recesses, a pair of insulating plates which are fitted to the terminal members to form one wall of the inclosing casing and one of which engages the recesses in said 25 terminal members, and a plurality of cap bushings fitted to the terminal members and 30 engaging holes which are located in that wall of the casing which is opposite the insulating plates.

3. In an electrical measuring instrument, the combination with a projection thereon 35 constituting a terminal casing, a plurality of terminal members in said casing having lateral recesses, and a pair of insulating plates therein that constitute a separating wall between the interior of the instrument 40 and the terminal casing and one of which engages said terminal member recesses.

4. The combination with a terminal casing, of a plurality of terminal members, and supporting and insulating means comprising 45 insulating plates which form one wall of the casing and one of which engages lateral recesses in said terminal members, and cap bushings of insulating material that are inserted in openings in the outer wall of the 50 casing.

5. The combination with an instrument casing having a terminal casing extension provided with a detachable front wall and with a plurality of openings in its top wall, a 55 plurality of terminal members, and means for supporting and insulating said members in said casing comprising insulating cap

bushings attached to said terminal members and fitted into the openings in the top wall of the casing and a pair of insulating plates fitted to said terminal members and constituting a separating wall between the body of the main casing and the terminal casing and one of which engages recesses in said 60 terminal members.

6. The combination with a terminal casing for electrical instruments, of a plurality of terminal members, and means for insulating and supporting said members in said casing comprising a pair of insulating plates which 70 form a separating wall between the interior of the instrument and the terminal casing and one of which engages notches in said terminal members.

7. The combination with a terminal casing 75 for electrical instruments, of a plurality of terminal members having lateral recesses, and a pair of insulating plates which are fitted to the terminal members to constitute one wall of the casing and one of which engages the recesses in said members.

8. In a terminal casing, the combination with a substantially cylindrical terminal member having a lateral recess and one side flattened near one end, of insulating plates 85 fitted to the terminal member at its flattened end and supported from the casing, one of which engages the lateral recess.

9. In a terminal structure, the combination with a plurality of cylindrical terminal 90 members having lateral recesses and flattened sides, of insulating plates which are fitted to the terminal members and one of which engages the lateral recesses and insulating bushings secured to one end of the terminal members.

10. In a terminal casing, the combination with cylindrical terminal members having lateral recesses and flattened sides, of insulating plates secured to the walls of the casing 100 and fitted to the terminals, one of which engages the lateral recesses, insulating bushings secured to the terminal members and projecting into holes in the casing walls, and means for securing conductors to either end 105 of the terminal members.

In testimony whereof, I have hereunto subscribed my name this 21st day of October 1905.

JOHN H. ZIMMERMANN.
